US00D773424S

(12) **United States Design Patent** (10) **Patent No.:** **US D773,424 S**
Wang (45) **Date of Patent:** **** Dec. 6, 2016**

(54) **MOBILE PHONE**

(71) Applicant: **Huawei Device Co., LTD**, Shenzhen (CN)

(72) Inventor: **Jiaxi Wang**, Shanghai (CN)

(73) Assignee: **Huawei Device Co., Ltd.**, Shenzhen (CN)

(**) Term: **14 Years**

(21) Appl. No.: **29/493,980**

(22) Filed: **Jun. 16, 2014**

(30) **Foreign Application Priority Data**

Dec. 16, 2013 (CN) 2013 3 0625121

(51) **LOC (10) Cl.** **14-03**

(52) **U.S. Cl.**

USPC ..... **D14/138 G**; D14/138 AA

(58) **Field of Classification Search**

USPC ..... D14/374, 138 AD, 138 G, 341; 455/575.1, 575.4

CPC H04M 1/0214; H04M 1/0237

See application file for complete search history.
